GAMEBOARD

John Kunsevich, 2959 Oceanside Road, Oceanside,
Long Island, N.Y.

Filed Feb. 18, 1964, Ser. No. 78,677

Term of patent 14 years

(Cl. D34—5)

FIG. 1

FIG. 2

FIG. 1 is a top plan view of a gameboard showing my new design; and

FIG. 2 is a typical edge view in elevation.

The views of all edges are the same as FIG. 2, and the bottom (not shown), opposite to FIG. 1, is solid and plain.

I claim:

The ornamental design for a gameboard, substantially as shown and described.
